UNITED STATES PATENT OFFICE.

CHARLES HERBERT DRAPER, OF CLEVELAND, OHIO, ASSIGNOR TO THE DRAPER MANUFACTURING COMPANY, OF CLEVELAND, OHIO, A CORPORATION OF OHIO.

METALLIC RECEPTACLE.

1,189,432.

Specification of Letters Patent.

Patented July 4, 1916.

Application filed May 29, 1908. Serial No. 436,144.

To all whom it may concern:

Be it known that I, CHARLES HERBERT DRAPER, a citizen of the United States of America, and a resident of Cleveland, in the county of Cuyahoga and State of Ohio, have invented certain new and useful Improvements in Metallic Receptacles, of which the following is a specification.

My invention relates to improvements in metallic receptacles, such as barrels or drums, and has for its object the provision of a containing vessel which shall be strong and durable for withstanding hard usage, and present liquid tight joints.

My improvements are more commonly utilized in the construction of metallic barrels which are adapted to contain any solid or liquid articles of commerce not likely to attack the metal. Accordingly, it is highly desirable that the necessary joints shall be liquid-proof, and so constructed as to avoid injury thereto causing leakage, under conditions of hard service.

Briefly referring to the features of construction about to be explained, I may say that a receptacle constructed in accordance with my invention comprises a body portion, which may be formed of suitable tubular lengths of seamless or jointed sheet metal.

The ends or closures thereof are formed of closely fitting heads or disks having upwardly and outwardly turned edges or lips, which with the extreme edges of the cylindrical body portion, are bent over to form a double locked joint. Interiorly of the annular joint thus formed, is positioned a rigid metal ring, preferably channeled to receive said double locked joint, and over the lower edge of the channel, the adjacent portions of the doubled metal are bent to lock said ring in place, and form a chime or supporting edge for the barrel or receptacle.

The details of this construction may best be gathered from the annexed drawings, wherein—

Figure I is a view in side elevation partially broken away, of a barrel constructed in accordance with my invention. Fig. II is an enlarged cross-sectional view showing in detail the preferred double locked joint within the channeled ring. Fig. III is a fragment partially broken away, showing the body of the receptacle. Fig. IV is a

cross-sectional view of the channeled ring. Fig. V is a cross-sectional view of the metallic head. Fig. VI is a fragmentary detail also in cross-section, illustrating the double locked joint before it is forced within the channel or recess; and Fig. VII is a fragmentary cross-sectional view of the double locked joint in association with a slightly modified channeled ring.

Throughout the several figures of the drawings I have employed the same character of reference to indicate similar parts.

It will be understood that the metallic receptacle herein shown is typical merely of the structural features of barrels or containing drums for any purpose whatsoever; some being successfully employed for the shipment of such commodities as kerosene or gasoline by reason of their tight joints which avoid material leakage or evaporation. These joints herein specifically set forth, are characterized by a closure comprising a double-locked joint or annular seam respectively, preferably compressed forcibly within a channeled ring substantially C-shaped in cross-section and of somewhat less minimum diameter externally, than the normal inner diameter of the receptacle.

The body portion *a* preferably is formed of cylindrical sheet metal, wherein the heads or closure parts *b* are adapted closely to fit. These closure parts ordinarily comprise a convex disk surrounded by an upturned rim *b'* and an outwardly turned flange *b*², which member being inserted within the cylindrical body portion, the adjacent edges or flanged rims *a*² *b*² are bent about each other, as best shown in initial form in Fig. VI to form a double locked seam or joint. The channeled ring *c* is then inserted within the recessed head, as shown, and the annular joint of the barrel-head is forced within the channel, tightly compressing the same, and closely drawing the metal faces *a*² *b*³ over the lower edge of the channeled ring, as best shown in Fig. II. By this means, not only are the advantages of a double locked joint attained, but the chime is given approximately a unitary construction, and strengthened to any necessary or desired extent by the heavy body of the channeled ring. As thus formed, the barrel is provided with a heavy chime sufficient for withstanding all

ordinary usage, and the supporting ring is held firmly in place by the inwardly bent edges or double locked joint.

Although the preferred construction is exhibited in Fig. II, the channeled ring *c* does not necessarily extend over or beyond the double locked joint, particularly when the receptacle is adapted for less severe service. For this construction, a modification, such as shown in Fig. VII, may be adopted, wherein the channeled ring is substantially flush with the outer portion of the double locked joint, and the channel proper is approximately of an irregular, unequal C-shape.

Having now described a receptacle or receptacles embodying my invention, I claim as new and desire to secure by Letters Patent, the following:

1. In a metallic receptacle, the combination with a body portion, of a head or closure part fitting therein, provided with upturned edges lying adjacent to the edges of the body portion, and bent over the same to form substantially a double locked joint, and an interiorly positioned channeled member substantially C-shaped in cross-section over the lower edge of which said double locked joint is bent to tighten and strengthen the same, substantially as set forth.

2. In a metallic receptacle, the combination with a cylindrical body portion formed of sheet metal, a disk-like metallic closure part inserted within the end of said body portion having upturned edges united with the edges of the body portion to form a substantially double locked joint, and a channeled ring substantially C-shaped in cross-section interiorly positioned within the head thus formed, wherein the double locked joint is compressed to form a supporting edge or chime, substantially as set forth.

3. In a metallic receptacle, the combination with a cylindrical body portion, of disk-like heads or closure parts provided

with upturned edges inserted within the ends of said body portion and united with the edges thereof to form double locked joints, a channeled ring substantially C-shaped in cross-section positioned interiorly of each of said joints and extending beyond the same, wherein said joints are compressed to form substantially integral chimes for the receptacle, substantially as set forth.

4. In a permanent closure for metallic receptacles, the combination with a substantially cylindrical body-portion formed of sheet metal, of a disk-like metallic closure part, inserted within the end of said body-portion, having upturned edges united with the edges of the body-portion to form an overlapped double-locked joint therewith, and a laterally channeled metallic ring substantially C-shaped in cross-section interiorly positioned within the annular joint thus formed, wherein said joint is recessed to form the chime, substantially as set forth.

5. In a metallic receptacle, the combination with the cylindrical body portion, of a cupped closure part fitting closely within the end thereof, and having an upturned lip extending beyond and turned over the edge of the body portion; the respective edges being again doubled over to form a tight joint, and an interior channeled ring substantially C-shaped in cross-section, but of less diameter than the body portion, annularly fitting within said cupped closure part, and extending beyond the joint, wherein the doubled edges are compressed for closing and strengthening the receptacle, substantially as set forth.

Signed at Cleveland, this 23rd day of May, A. D., 1908, in the presence of two subscribing witnesses.

CHARLES HERBERT DRAPER.
